UNITED STATES PATENT OFFICE

GEORGE B. PITTS, OF CLEVELAND, OHIO, ASSIGNOR, BY MESNE ASSIGNMENTS, TO THE MILLER PASTEURIZING MACHINE COMPANY, OF CANTON, OHIO, A CORPORATION OF OHIO.

PASTEURIZING APPARATUS.

1,300,869.

Specification of Letters Patent.

Patented Apr. 15, 1919.

Application filed August 29, 1917. Serial No. 188,749.

To all whom it may concern:

Be it known that I, GEORGE B. PITTS, a citizen of the United States, residing at Cleveland, in the county of Cuyahoga and State of Ohio, have invented certain new and useful Improvements in and Relating to Pasteurizing Apparatus, of which the following is a specification.

This invention relates to pasteurizing or liquid treating apparatus, particularly apparatus of the type shown in Letters Patent No. 1,185,531, granted May 30, 1916, to Leroy S. Pfouts.

The invention is adapted for use in connection with liquid treating apparatus of the character disclosed in U. S. Letters Patent No. 1,183,764, granted to Leroy S. Pfouts. However, the invention may be used in connection with liquid treating apparatus of any desired construction.

The objects of the invention are to simplify the construction of apparatus of this character, to prevent loss of heat from the liquid being treated, and to increase the efficiency and capacity of the apparatus.

Other objects of the invention will be apparent to those skilled in the art from the following description, in which

Figure 1 is a view, partly in elevation and partly in section, of an apparatus embodying my invention.

Fig. 2 is a view of the apparatus, looking toward the right in Fig. 1, parts being broken away.

Fig. 3 is a top plan view of the apparatus, two of the holders being removed.

Fig. 4 is a section on the line 4—4 of Fig. 1.

Fig. 5 is a fragmentary sectional view.

In the drawings, 1 indicates as an entirety a support. The support 1 preferably comprises a table 1^a, a plurality of legs 1^b on which the table 1^a is mounted, and a base 1^c, to which the legs 1^b may be secured in any well known manner. The table 1^a may comprise a pair of superposed annular members 1^{a'}, 1^{a''}, the lower one 1^{a'} thereof being secured to the legs 1^b in any suitable way and forming with the latter and base 1^c a rigid framework to support a series of liquid holders 9 and a driving mechanism 2. The upper annular member 1^{a''} rests upon the

lower member 1^{a'}, if desired, it may be detachably secured thereto in any well known manner. The upper annular member 1^{a''} 55 may be provided on its upper face with vertical walls 1^d, extending radially and around the outer edge of the member to form pockets or recesses for removably receiving the holders 9.

1^e indicates one or more cross members, connected at their opposite ends in any well known manner to the legs 1^b. The cross members 1^e are provided with a bearing to support a shaft 4^a of a valve mechanism 4, 65 which will be later described. At its lower end the shaft 4^a has fixed to it a worm gear 4^x.

3 indicates a sub-support which may be secured in any suitable manner to two of the 70 legs 1^b. 3^a indicates a bracket fixed to the sub-support and provided with a bearing 3^b. 5 indicates a shaft, mounted in the bearing 3^b, and carrying at its outer end fast and loose pulleys 5^a for a belt (not shown). 6 75 indicates a pair of spaced lugs fixed in any preferred manner to the sub-support 3, and 6^a indicates a rod supported at its opposite ends in openings formed in the free ends of the lugs 6. 6^b indicates a collar or sleeve, 80 rotatably mounted on the rod 6^a and carrying a pair of arms 6^{b'}. The arms 6^{b'} are formed with aligned openings to receive and support a shaft 5'. 7 indicates a worm fixed to the shaft 5' between the arms 6^{b'} and 85 adapted to mesh with the worm gear 4^x. The worm 7 is of a length to occupy the space between the arms 6^{b'}. The arms 6^{b'} therefor take the end thrusts of the worm 7. The collar 6^b is rotated in one direction on 90 the rod 6^a to move the worm 7 into engagement with the worm gear 4^x, as shown in Figs. 1 and 2; the collar is rotated in the opposite direction to disengage the worm 7 from the worm gear 4^x, for a purpose to be 95 later described. When the worm 7 is in mesh with the worm gear 4^x, the shaft 5' is preferably in alignment with the shaft 5 and may be connected thereto by any suitable means, such as a connector 8. The connector 8 may comprise a sleeve adapted to move endwise on the shaft 5 and receive within its open end the adjacent end of the shaft 5'. The walls of the sleeve opening and shaft

end are suitably shaped to cause a locking or driving connection between them. The collar 8 is preferably fixed to the shaft 5 by a set screw 8^a when it is either connected to or 5 disconnected from the shaft 5.

The holders 9 are arranged in a circular series about the axis on the table 1^a. They are preferably V-shaped in cross section in order that the maximum number can be provided on the table 1^a and all have their inner 10 end walls terminate at an equal distance from a common center, which by preference is the center of the table 1^a. The holders 9 may be of a size and shape to exactly fit 15 within the pockets formed by the walls 1^a; in that event the latter serve to maintain the holders 9 stationary and against movement outwardly or inwardly. Each holder comprises a bottom wall 9^a, an outer end wall 9^b, 20 side walls 9^c, a removable top wall or cover 9^d and an inner end wall 10. At its lower end, the inner end wall 10 is formed with an opening 10^a, to which reference will later be made. The opening 10^a in the end wall of 25 each holder is arranged at or adjacent the bottom wall thereof. This permits the liquid delivered to the holder to rise therein, thus eliminating agitation and foaming or frothing thereof; it also permits all of the 30 liquid to flow out of the holder by gravity. The bottom wall of each holder may be inclined downwardly toward its inner end wall to insure complete emptying of the liquid therefrom. Each wall may be constructed 35 as shown in Fig. 5, to prevent the loss of heat from the liquid in the holder; that is, each wall may comprise spaced plates 9^e to form between them a space which is filled with a suitable heat non-conducting material 40 such as cork.

The valve mechanism 4 includes a valve member 4^a which co-operates with the end walls 10 to control the flow of the liquid to and from the holders or vessels 9. The 45 valve member 4^a preferably comprises a circular plate 4^a the side wall of which may be of conical shape, and a socket member 4^b to receive the upper end of the shaft 4^a. The upper end of the shaft 4^a is squared or 50 otherwise shaped and the socket member is similarly shaped to receive the shaft end and be driven thereby. The valve member 4^a is formed with two ducts 4^b, 4^c. The duct 4^b serves as a conduit for the liquid as 55 it flows to the holders or vessels 9, its inner end opening upwardly preferably centrally of the valve member 4^a and its opposite or outer end leading through the conical side wall of the plate 4^a and successively registers with the openings 10^a leading through the inner end walls 10 of the holders 9. The duct 4^c successively registers with the openings 10^a and conducts the liquid through the valve member 4^a from a holder or vessel 9

when the latter is emptying, its receiving 65 end or port leading through the conical side wall of the plate 4^a, and preferably adjacent to the port of the duct 4^b, and its opposite end or discharge port opening downwardly at one side of the shaft 4^a, as shown 70 in the drawings. When the holders 9 are arranged in assembled position (see Fig. 3), their inner end walls 10 are arranged substantially edge to edge. In the event the edges of the inner end walls do not meet, suitable 75 spacing devices may be placed between them to form a continuous seat or wall for the valve member 4^a. As shown in Fig. 4, the walls 10 are arranged about the axis of the table 1^a or shaft 4^a, so that when the 80 holders are assembled, the walls 10 thereof co-operate to form a seat for the valve member 4^a. To provide a suitable bearing face for the side or conical wall of the valve member 4^a, I prefer to thicken the lower portion 85 of the inner end of wall 10, as shown at 10', and to both curve and incline the outer face of this thickened portion to adapt it to the shape of the valve member 4^a. The thickened portion 10' may comprise a plate 90 of suitable material which permits accurate grinding, fixed to the wall 10 in any suitable manner.

From the foregoing description, it will be 95 seen that the valve member 4^a rotates in direct engagement with the inner end walls of the holders 9, the ducts of the valve member registering with the openings 10^a to control the flow of the liquid to and from the holders 9. It will also be seen that each holder is 100 formed with a single opening through which the liquid flows both to fill and empty the holder. By reason of such construction, the liquid flows directly from the valve member to each holder when the latter is filling; when each holder is emptying the liquid flows therefrom directly to the valve member. In other words, the holders 9 and valve member 4^a are correlated with each other in 105 a manner which makes it unnecessary to provide conduits for the liquid of any kind whatsoever between the valve member and the holders. This form of construction prevents loss of heat from the liquid due to its flow through conduits between the valve 115 member and the holders. It insures that all of the liquid flowing through the duct 4^b will enter an adjacent holder 9 and be treated therein for the desired predetermined time and at the desired temperature; it also insures that little, if any, agitation of the liquid will take place.

By preference, the wall 1^a extends entirely around each holder 9 to form a complete 120 pocket therefor. This form of construction has many advantages, for instance, it insures correct positioning of the holder in its pocket and it forms a suitable support for

and permits the use of an annular valve seat member, such as shown in Fig. 4. When the table member 1^{ax} is constructed in this manner, the vertical wall 1^d is formed with a 5 port to register with each opening 10^a.

11 indicates a receiving chamber preferably arranged substantially axially of the holders 9 and slightly elevated relative thereto to permit the flow of the liquid by 10 gravity to the holders. The chamber 11 is provided with a suitable cover 11' through which extends the discharge end of a pipe 10^a, to conduct the liquid in a substantially continuous and uniform manner from the 15 liquid trough or discharge duct of a suitable liquid heater (not shown) to the chamber 11. Each wall of the chamber 11 may be formed of two parts or members, an outer member and an inner member, between 20 which is provided a suitable insulating jacket, similar to the construction of the holders 9, as shown in Fig. 5. The chamber 11 may be provided with an axially arranged outlet pipe section 11^a, which is detachably 25 connected in any preferred manner to the upper end of a conduit 11^c. The lower end of the conduit 11^c is detachably connected in any well known manner to a coupling 11^f, which in turn may be screw-threaded in the 30 inner end or opening for the duct 4^b. The pipe or conduit 11^c and its connections with the chamber 11 and valve member 4^a preferably serve as the means for supporting the chamber 11 upon the latter and at a 35 suitable height to effect the flow of the liquid through the apparatus.

It will be noted that the connection between the discharge end of the pipe 10^a and the cover 11' of the chamber 11 is of a character which permits the chamber and cover to rotate relative thereto without affecting the discharge of the liquid from the pipe 10^a. Preferably the pipe 10^a extends through an axial opening in the cover 11' and the latter may be provided with a bearing which 45 loosely receives the said pipe.

11^x indicates a depending discharge pipe connected with the discharge end of the duct 4^c. The pipe 11^x is open at its lower end 50 and discharges the liquid into an annular receptacle 12. The pipe 11^x may comprise a plurality of sections detachably connected together in any suitable manner, as indicated at 11^x. The receptacle 12 is preferably supported by the cross members 1^e. At 55 one side its bottom is formed with a discharge opening to which is connected a conduit 12^a leading to a point of delivery, such as a cooler (not shown) or a receiving tank therefor. A suitable cut-off valve 12^b may be provided in the conduit 12^a.

13 indicates a pipe or conduit leading from the pipe 10^a and connected at its outer end to the delivery pipe 12^a. A valve, pref-

erably of the three-way type, may be inter- 65 posed at the connection of the pipe 13 with the pipe 10^a to control the flow of the liquid to either the distributing and holding apparatus or direct to the delivery pipe 12^a which leads to the cooler, or to cut off the 70 flow of the liquid entirely. The pipes 13 and 12^a may be used to conduct the liquid from the heater to the cooler when it is unnecessary to treat the liquid in the holding apparatus. The pipes 10^a, 13 and 12^a may 75 be formed in sections and connected together by couplings 13^a, in a well known manner.

The conical valve member 4^a' and the co-operating seats therefor may be shaped to permit the removal of the valve member 4^a' 80 either upwardly or downwardly. Preferably I provide for the removal of the valve member downwardly. For this purpose, I provide for the endwise movement of the shaft 4^a to disconnect its upper end from 85 the socket of the valve member 4^a'. 14 indicates a sleeve surrounding the shaft 4^a but connected thereto in a manner to cause movement of the shaft with the sleeve when the latter is moved endwise. The sleeve 14 90 is slidably mounted in the bearing for the shaft and at one side it is provided with a rack 14^a. 15 indicates a shaft having support at one end in the shaft bearing and at its other end in one of the legs 1^b. At its 95 outer end the shaft 15 carries a crank 15^a. At its inner end the shaft carries a pinion 16 which meshes with the rack 14^a. To cause the disconnection of the shaft 4^a from the socket of the valve member 4^a' it is first necessary to disconnect the connector 8 from the shaft 5', then to rotate sleeve 6^b on the rod 6^a. This latter operation disengages the worm 7 from the gear 4^x; thereafter, by operating the crank 15^a, the pinion 16 may be 100 rotated and it in turn through the rack 14^a and sleeve 14 will move the shaft 4^a downwardly. The valve member 4^a may then be removed. When the valve member is replaced the shaft 4^a is moved upwardly by the 105 operation of the pinion 16 in the opposite direction.

I prefer to provide compression means, indicated as an entirety at 17, for normally maintaining the valve member 4^a in engagement with its seat walls 10 so that the valve member will be yieldingly maintained thereagainst at all times while being rotated by the shaft 4^a. Of these means, 17^a indicates a collar surrounding and fitting the upper 110 end of the shaft 4^a. The collar 17^a rests upon the upper end of the sleeve 14, or suitable washers thereon, so as to be thrust upwardly thereby when it and the shaft are moved upwardly. At its upper end the collar is enlarged to form an annular recess 17^b. 17^c is a coiled spring interposed between the collar 17^a and the valve member 4^a'. The 115 120 125

coiled spring preferably surrounds the socket member of the valve, its lower end being seated in the recess 17^b and its upper end engaging with the lower side of the 5 valve member. When the sleeve 14 and shaft 4^a are moved upwardly, the coiled spring is compressed between the collar 17^a and the valve member 4^{a'} and normally tends to press the latter upwardly with its 10 annular wall in close engagement with the walls 10, thereby making the valve substantially liquid tight.

From the foregoing description it will be understood that the holders 9, or the inner 15 end walls 10 thereof, and the valve member 4^{a'}, constitute a valve mechanism which controls the flow of the liquid to and from the holders or vessels 9 as the openings of the ports 4^b, 4^c, successively register with the 20 openings 10^a.

During the time that the opening 10^a for an adjacent holder or vessel 9 and the duct 4^b are in registry, as the valve member 4^{a'} rotates, liquid will flow therethrough from the 25 chamber 11 to the holder to fill the same, the speed of the valve member 4^{a'} and the size of the openings 4^b, 10^a, being proportioned so that during the registry thereof sufficient liquid will flow through the valve 30 to substantially fill the vessel.

The liquid is held in the vessel 9 during the rotary movement of the valve member 4^{a'} until the port of the discharge duct 4^c registers with the valve opening 10^a, where- 35 upon the liquid will flow by gravity from the vessel or holder through the valve opening 10^a and duct 4^c to the discharge pipe 11^c. As the ducts 4^b, 4^c, and the valve ports there- 40 of are of substantially the same size, and the valve member 4^{a'} rotates uniformly, it will be understood that substantially the same quantity of liquid may flow out of each ves- 45 sel as flowed into it in the same time in- terval. The valve port for the duct 4^c is preferably arranged in the conical wall of the valve member 4^{a'} immediately forward of the valve port for the duct 4^b, so that the filling operation for each vessel will follow immediately after it has been emptied. This 50 arrangement provides for the operation of filling vessels progressively and emptying them progressively; it also provides for the operation of filling and emptying adjacent vessels simultaneously.

55 The liquid is delivered to a receiving tank from which it flows by gravity to the heater. In passing through the heater the liquid is suddenly and uniformly raised to the desired temperature and is discharged from 60 the heater by means of the conduit α^{10} , which conveys the liquid to the receiving chamber 11. As the valve member 4^{a'} rotates, the duct 4^b thereof registers successively with the valve openings 10^a in the walls 10 and

permits a predetermined quantity of liquid 65 to flow by gravity to each of the vessels, the port of the duct registering with each valve opening 10^a for a given period of time in the rotary movement of the valve member, suffi- 70 cient, at least, to substantially fill the adja- cent holder. Likewise, the discharge duct 4^c registers successively with each valve opening 10^a and permits the automatic dis- charge of the vessels successively.

The duct 4^c of the valve mechanism 4 may 75 be arranged at any predetermined point an- gularly of the axis of the valve member 4^{a'} relative to the duct 4^b, so that the distance of travel of the valve member 4^{a'} from the position for filling to the position for empty- 80 ing may be of proper length in order that the period for holding the liquid may be fixed according to any particular circum- 85 stances desired. From this construction and operation, it will be seen that the vessels will 90 be automatically filled and emptied at prede- termined points and that the liquid in each vessel will be held therein for a prede- 95 termined period, the extent of which depends upon the length and time of travel from the place of filling to the place of discharge. It will be obvious that the speed of the valve member can be changed in various ways to increase or decrease the period between the filling and emptying of the vessels. 95

The simplicity of the construction makes it possible to readily disassemble and clean all parts of the apparatus.

To those skilled in the art of making ap- 100 paratus of the class described, many altera- tions in construction and widely differing embodiments and applications of my invention will suggest themselves, without depart- 105 ing from the spirit and scope thereof. My disclosures and the description herein are purely illustrative and are not intended to be in any sense limiting.

What I claim is:

1. In apparatus of the class described, the combination of a plurality of holders each 110 formed with an opening in one wall, a valve member having a delivery duct and a dis- charge duct, the outlet and inlet ports of 115 which register with the openings in the walls of the holders, means for supplying liquid to the inlet port of said delivery duct, means for conveying away the liquid from the outlet port of the discharge duct, and means for causing relative movement be- 120 tween said series of holders and said valve member.

2. In apparatus of the class described, the combination of a plurality of holders ar- 125 ranged in a circular series and coöperating to form a seat for a rotary valve, each holder being formed with an opening through which the liquid flows into and therefrom, a valve rotatably supported in the seat formed

- by said holders and formed with a delivery duct and a discharge duct, the ports of which register with the openings formed in said holders, means for supplying liquid to 65
 5 the delivery duct of said valve, means for conveying away the liquid from the discharge duct of said valve, and means for rotating the said valve.
3. In apparatus of the class described, the 10 combination of a plurality of holders arranged in a circular series and coöperating to form a seat for a rotary valve, each holder being formed with an opening through which the liquid flows into and therefrom, a 15 valve rotatably supported in the seat formed by said holders and formed with a delivery duct and a discharge duct, the ports of which register with the openings formed in said holders, means for supplying liquid to 20 the delivery duct of said valve, means for conveying away the liquid from the discharge duct of said valve, means for rotating the said valve, and means for yieldingly maintaining said valve in operative position.
- 25 4. In apparatus of the class described, the combination of a plurality of holders arranged in a circular series, the inner end wall of each holder being formed with an opening in line with the bottom of said 30 holder through which liquid flows into and out of the holder, and a valve having rotative engagement with the inner end walls of said holders and formed with two ducts, the ports of which register with the openings in 35 said inner end walls and control the flow of liquid therethrough in opposite directions, means for supplying liquid to the delivery duct of said valve, means for conveying away the liquid from the discharge duct of 40 said valve, and means for rotating said valve.
5. In apparatus of the class described, the combination of a plurality of holders arranged in a circular series, the inner end 45 wall of each holder being formed with an opening in line with the bottom of said holder through which liquid flows into and out of the holder and the bottom of said holder being inclined toward the inner end 50 wall thereof, and a valve having rotative engagement with the inner end walls of said holders and formed with two ducts, the ports of which register with the openings in said inner end walls and control the flow of liquid therethrough in opposite directions, means for supplying liquid to the delivery 55 duct of said valve, means for conveying away the liquid from the discharge duct of said valve, and means for rotating said valve.
6. In apparatus of the class described, the combination of a series of holders arranged about a common axis, the inner end walls of said holders being curved and coöperat- 60 ing to form a seat, a valve mounted to 65 rotate in the seat formed by said inner end walls, each said inner end wall being formed with an opening and said valve being formed with a delivery duct and a discharge duct, the ports of which register with 70 said openings, whereby the liquid is delivered directly to and discharged directly from said holders, means for supplying liquid to said delivery duct, means for conveying away the liquid from said discharge 75 duct, and means for rotating said valve.
7. In apparatus of the class described, the combination of a series of holders arranged about a common axis, the inner end walls of said holders being curved and coöperating to form a seat, a removable valve mounted to 80 rotate in the seat formed by said inner end walls, each said inner end wall being formed with an opening and said valve being formed with a delivery duct and a discharge duct, the ports of which register with 85 said openings, whereby the liquid is delivered directly to and discharged directly from said holders, means for supplying liquid to said delivery duct, means for conveying away the liquid from said discharge duct, and means for rotating said valve.
8. In apparatus of the class described, the combination of a series of holders arranged about a common axis, the inner vertical end walls of said holders having curved portions which coöperate to form a seat, a valve mounted on a vertical axis to rotate in the 90 seat formed by said inner end walls, each inner vertical end wall being formed with an opening and said valve being formed with a delivery duct and a discharge duct, the ports of which register with said opening, whereby the liquid is delivered directly to and discharged directly from said holders, means for supplying liquid to said delivery duct, means for conveying away the liquid from said discharge duct, and means for rotating said valve.
9. The combination of a series of vessels having inner vertical end walls arranged concentric to a common axis and coöperating to form a seat for a valve, a valve supported on a vertical axis to rotate in the seat formed by said inner end walls, each inner end wall being formed with a single opening through which liquid flows into and out of said holder and the valve being formed with a delivery duct and a discharge duct, the ports of which register with said opening, means for maintaining uninterrupted communication between the inner port of the delivery duct of said valve member and a source of liquid supply, means for receiving the liquid discharged by the discharge duct of said valve, and means for 100 rotating said valve.
10. The combination of a series of vessels having inner vertical end walls arranged concentric to a common axis and coöperating to form a seat for a valve, a valve supported on a vertical axis to rotate in the seat formed by said inner end walls, each inner end wall being formed with a single opening through which liquid flows into and out of said holder and the valve being formed with a delivery duct and a discharge duct, the ports of which register with said opening, means for maintaining uninterrupted communication between the inner port of the delivery duct of said valve member and a source of liquid supply, means for receiving the liquid discharged by the discharge duct of said valve, and means for 105 rotating said valve.
11. The combination of a series of vessels having inner vertical end walls arranged concentric to a common axis and coöperating to form a seat for a valve, a valve supported on a vertical axis to rotate in the seat formed by said inner end walls, each inner end wall being formed with a single opening through which liquid flows into and out of said holder and the valve being formed with a delivery duct and a discharge duct, the ports of which register with said opening, means for maintaining uninterrupted communication between the inner port of the delivery duct of said valve member and a source of liquid supply, means for receiving the liquid discharged by the discharge duct of said valve, and means for 110 rotating said valve.
12. The combination of a series of vessels having inner vertical end walls arranged concentric to a common axis and coöperating to form a seat for a valve, a valve supported on a vertical axis to rotate in the seat formed by said inner end walls, each inner end wall being formed with a single opening through which liquid flows into and out of said holder and the valve being formed with a delivery duct and a discharge duct, the ports of which register with said opening, means for maintaining uninterrupted communication between the inner port of the delivery duct of said valve member and a source of liquid supply, means for receiving the liquid discharged by the discharge duct of said valve, and means for 115 rotating said valve.
13. The combination of a series of vessels having inner vertical end walls arranged concentric to a common axis and coöperating to form a seat for a valve, a valve supported on a vertical axis to rotate in the seat formed by said inner end walls, each inner end wall being formed with a single opening through which liquid flows into and out of said holder and the valve being formed with a delivery duct and a discharge duct, the ports of which register with said opening, means for maintaining uninterrupted communication between the inner port of the delivery duct of said valve member and a source of liquid supply, means for receiving the liquid discharged by the discharge duct of said valve, and means for 120 rotating said valve.
14. The combination of a series of vessels having inner vertical end walls arranged concentric to a common axis and coöperating to form a seat for a valve, a valve supported on a vertical axis to rotate in the seat formed by said inner end walls, each inner end wall being formed with a single opening through which liquid flows into and out of said holder and the valve being formed with a delivery duct and a discharge duct, the ports of which register with said opening, means for maintaining uninterrupted communication between the inner port of the delivery duct of said valve member and a source of liquid supply, means for receiving the liquid discharged by the discharge duct of said valve, and means for 125 rotating said valve.

10. In apparatus of the class described, the combination of a plurality of holders each formed with a single opening in one wall through which the holder is filled and emptied, a valve member having a delivery duct and a discharge duct, the outlet and inlet ports of which register with the openings in the walls of the holders to control the filling and emptying thereof, means for

supplying liquid to the inlet port of said delivery duct, means for conveying away the liquid from the outlet port of the discharge duct, and means for causing relative movement between said holders and said valve member.

15 In testimony whereof I affix my signature.

GEORGE B. PITTS.
